UNITED STATES PATENT OFFICE.

JOHN A. BASSETT, OF SALEM, MASSACHUSETTS.

IMPROVEMENT IN APPARATUS FOR CARBURETING GAS.

Specification forming part of Letters Patent No. 35,981, dated July 29, 1862.

To all whom it may concern:

Be it known that I, JOHN A. BASSETT, of Salem, in the county of Essex and State of Massachusetts, have invented a new and useful Improvement in Apparatus for Carbureting Gas; and I do hereby declare that the following is a full and exact description of the same, reference being had to the drawings annexed to this specification, which represent in section an apparatus applied to a lamp-post, and an enlarged view of the same.

The nature of my invention consists in providing the outlet of a gas-burner with a wick-tube or its equivalent, connected with a reservoir of hydrocarbon liquid—as naphtha or benzole—the burner and the tip being made separate, the tip fitting into the top of it and confining the wick-tube at that point. The reservoir of naphtha is placed at some convenient point to connect the gas-burner with it. The wick serves by capillary attraction to absorb and take up the naphtha and convey it to the tip, where, by the heat of the burning gas acting upon the tip and the burner, it is volatilized and mixed with the gas as it issues from the burner, and the supply being constantly kept up, the gas is fully carbureted, whatever may be the surrounding temperature, the particular object of the invention being to overcome the difficulty of carbureting gas at low temperatures; and this is accomplished in the most thorough manner by keeping the hydrocarbon liquid at the point where it is kept warm by the heat of the gas, so that it is carbureted uniformly, whatever is the surrounding temperature; and this is an important desideratum in exposed places, as street-lamps, where this invention works most perfectly.

To enable others skilled in the art to make and use my invention, I will proceed to describe the same with reference to the drawings.

Figure 1 is a view of the apparatus applied to a lamp-post, Fig. 2 being an enlarged view of the same.

The same letters of reference apply to both drawings.

I construct the vessel A, for holding the liquid hydrocarbon, of cylindrical or other shape, as is most convenient for the place it is to occupy, of tin or other suitable material, and connect it at the lower end with the inlet gas-pipe

B. A continuation of this pipe extends up into the vessel above the level of the hydrocarbon liquid C. To the top of this vessel I attach an outlet-pipe, D, and on the top of this is screwed the burner E. The burner E is a chambered one, having a separate tip, F, which is driven into the top of the burner gas-tight. From the top of the burner, extending down through the tube D into the reservoir of hydrocarbon liquid A, is placed the wick-tube H; and among other means I make this wick-tube of braided lamp-wicking, with the central strand drawn out, leaving a hollow tube. The top of the tube is stretched over the top of the burner, which leaves an opening into which the tip F is driven gas-tight, confining the tube at the top of the burner, and inclosing the lower part of the tip in a porous tube, through which the gas must pass to get out of the orifices of the burner.

The tip F should be made of iron, brass, or some good conductor when a hydrocarbon liquid is used, which is not volatile; but where a very volatile liquid is used, it is better to put in a lava or steatite tip, or one made of clay, which will conduct heat enough to supply the flame. The tip should be partly in and partly out of the shell of the burner.

I prefer to have a chamber in the burner, in order to allow the gas to expand and become warmed before it enters the tube surrounding the tip. By this means less heat is abstracted from the tip.

If a very volatile hydrocarbon liquid is used, a cap may be placed over the burner when it is not in use, in order to prevent the evaporation which would take place in warm weather.

If the burner is placed very close to the hydrocarbon-reservoir, I should prefer to use a non-conductor placed between the burner and the pipe connecting the reservoir, in order to prevent the heat from vaporizing the naphtha in the vessel. As a general rule, however, this will not be required, except in the use of a very volatile hydrocarbon liquid. By the use of this arrangement a hydrocarbon may be used to carbure the gas which is not at all volatile. Crude rosin, naphtha, and even some of the lighter kinds of petroleum oils may be used. This is an important object, on account of economy and safety.

In case a heavy hydrocarbon liquid is used,

a tip should be placed in the burner having the greatest conducting power. Either brass or copper should be used.

A plug, I, is employed to close the opening used to replenish the hydrocarbon liquid.

The great difficulty in carbureting gas is that under a low temperature the hydrocarbon liquid does not vaporize and the gas does not take it up. Another trouble is that by evaporation the liquid becomes so much cooled that it does not vaporize. This apparatus is not liable to any of these contingencies, but will carburet gas at zero, as well as at a more elevated temperature.

I wish it distinctly understood that the object of this invention is entirely different from those vapor-burners used in lamps in which a burner, like a gas-burner, has the fluid conveyed to it by a wick and is then vaporized, the arrangement described being for an entirely different purpose, it being entirely impossible to burn the hydrocarbon liquid through the burner used without the aid of the gas.

It will be seen that the gas is carbureted by passing through the part of the wick which is saturated with hot naphtha or hydrocarbon liquid. In order to get at the orifices of the burner, the gas passes up to the highest part of it, being warmed in its passage, and then passes through the wick-tube just at the point where it can be best carbureted.

No claim of novelty is made to placing a reservoir of hydrocarbon liquid near the burner, this device being old and well-known.

Having thus fully described the nature of my invention, what I claim therein as new, and desire to secure by Letters Patent, is—

The arrangement, substantially as described, of a gas-carbureting burner with the tube H, of porous or textile material, connected with the tip F of the burner, and in communication with a hydrocarbon-reservoir, as set forth.

JOHN A. BASSETT.
